WALTER E. LARSON AND JOHN H. KOHLER, OF PITTSBURGH, PENNSYLVANIA, ASSIGNEES, BY MESNE ASSIGNMENTS, TO WALKER MANUFACTURING COMPANY, OF RACINE, WISCONSIN, A CORPORATION OF WISCONSIN

JACK HANDLE

Application filed August 8, 1927. Serial No. 211,415.

This invention relates to operating handles and more particularly to handles for operating that type of jacks having a rotary actuating member.

5 Jack handles have been provided that collapse in the middle so that they may be more conveniently carried in an automobile and like vehicle but this construction has not provided a satisfactory means for rendering the hinge portion of the handle in a rigid fixed 10 position when in alined operative position and thereby renders the handle useless in pushing the jack under the car, the advisability of which is obvious to those acquainted 15 with the use of this device.

An object of this invention is to provide a collapsible jack handle comprising a plurality of relatively movable links and means for rendering the links in rigid fixed relation 20 when they are in alined operative positions.

Another object of this invention is to provide a folding jack handle comprising a plurality of collapsible links and a novel means for connecting the said links.

25 These and other objects that may be made apparent throughout the further description of the invention are attained by means of the device hereinafter described and illustrated in the accompanying drawings, wherein

30 Figure 1 is an elevational view of a jack handle embodying the invention.

Fig. 2 is an elevational view of a portion of Fig. 1 turned at 90°.

Figs. 3 and 4 are fragmental views of one 35 end of a link disposed at 90° one to the other.

Figs. 5 and 6 are fragmental views of the other end of a link disposed at 90° one to the other.

Fig. 7 is a fragmental view partly in cross 40 section showing the hand grip of the actuating portion of the handle and,

Fig. 8 is a fragmental view partly in cross section of the main portion of the jack handle showing a hand grip.

45 This invention comprises in general a col-

lapsable jack handle having one of its ends adapted to engage a jack and an actuating member disposed on its other end for actuating the handle and a main body portion comprising a plurality of collapsible interchangeable links and means for releasably and rigidly clamping the links in alined operative position. 50

The handle is provided at one of its ends with a portion 11 adapted to engage a jack, an actuating member 12 disposed on the other end of the jack handle of the usual conventional type having in addition a novel grip handle 13 disposed on its free end and means 14 disposed on the other end for connecting the member 12 with the main body portion 15 of the handle. The main body portion 16 represented in its entirety by 15 will be hereinafter described. 55

The main body portion 15 consists of a plurality of interchangeable links 16 of any predetermined length and it is apparent that any number of these links may be used to obtain a jack handle of any desired length. 60

The means 14 for connecting the links are best understood by referring to Figs. 3, 4, 5 and 6. Figs. 3 and 4 illustrate the construction of one end of the link 16 showing a flange portion 17 having a diameter of substantially half the diameter of the body portion of the link 16, the flange portion 17 having an extended lug or ear at right angles to the axes of the link. The flange portion 17 is provided with an opening 18 and a projection 19 the purpose of which will be described below 65 in connection with the construction of the other end of the link or the cooperating end of an adjacent link. Figs. 5 and 6 illustrate the other end of the link 16 having a flange portion 21 of substantially the same shape 70 as the flange portion 17 on the other end and having an opening 22 and a groove 23 for registering and receiving the opening 18 and projection 19 respectively of a cooperating 75 link 16. It will therefore be understood that 80

85 90

Figs. 3 and 4 illustrate one end of a link 16 and Figs. 5 and 6 illustrate the other end.

In assembling the jack handle the cooperating ends of a pair of links are placed in engagement with each other, alining the openings 18 and 22 and the projection 19 and groove 23 respectively. The openings 18 and 22 are adapted to receive any suitable clamping means such as a bolt 24 having a clamping nut 25 for rigidly clamping the links together or releasing them to such extent as will permit the disengagement of the projection 19 from the groove 23 and permit the links to be rotated about the bolt 24 in a lateral direction towards one another.

The links 16 are provided with beveled portions 26 adjacent each of the flange portions 17 and 18 for permitting lateral movement of the cooperating links when the clamping bolt 24 is released and the projection 19 is disengaged from the groove 23.

It can be seen from Fig. 1 that the lugs or ears of flanges 17 and 21 terminate in a direction substantially at right angles with the axis of the link 16 and in opposite directions for permitting the collapsing of adjacent links 16 in opposite directions.

The end of the portion 11 adjacent the link 16 is provided with a flange constructed similarly to that provided for one end of a link 16 and one end of the actuating portion 12 is provided with a flange constructed substantially the same as the other end of the link 16 thereby permitting the connection of the actuating portion 12 to the portion 11 or to any link extending from the portion 11.

The link 16 adapted to be positioned adjacent the actuating portion 12 is provided with a hand grip 27 of cylindrical shape enclosing a portion of the link 16. This link 16 is also provided with integral collars 28 and 29 for maintaining the hand grip 27 in the desired position. The link 16 is adapted to rotate freely within the hand grip.

The free end of the actuating member 12 is provided with a hand grip 13 as above stated. The hand grip 13 having an inwardly curved portion 31 is adapted to cooperate with a groove 32 in the free end of the actuating member 12 for maintaining the grip 13 in position. The free end of the member 12 is adapted to rotate freely within the hand grip 13 so that the surface of the hand grip 27 and 13 will remain stationary with respect to the surface of the operator's hand and permit the associating part of the handle to move free therein.

It will be seen from the above description that we have provided a collapsible operating handle comprising a plurality of interchangeable links that will permit the handle to be folded up into a compact arrangement and means associated with the links for securing the links in rigid fixed relation when the links are in alined operative position.

While we have illustrated and described but one embodiment of this invention it will be apparent to those skilled in the art that certain changes, modifications, substitutions, additions and omissions may be made in the apparatus described without departing from the spirit and scope of the appended claims.

We claim:

1. A folding jack handle comprising a plurality of interchangeable links, each of said links being adapted to fold in opposite directions to its adjacent link and means for rigidly clamping the said links in fixed relation when the said links are in alined position, the said means comprising a groove in one end of each link for receiving a projection on the cooperating end of another link and a clamping device extending through openings in the cooperating ends of the links.

2. A joint for fastening a plurality of metal links together, comprising a flanged portion on the end of the one link having an off-center cylindrical opening and a groove therein, a flanged portion on a second link having an off-center cylindrical opening and a projection thereon adapted to cooperate with the opening and groove on the first link, and means extending through the corresponding cylindrical openings when the links are in aligned position to rigidly hold the said links in fixed relation to each other.

3. A joint for fastening a plurality of metal links together, comprising a flanged end portion on one link, said flanged end having an extended lug and being provided with an off-center cylindrical opening and a projection, a cooperating flanged end portion on a second link, said flanged end having an extended lug and being provided with an off-center cylindrical opening and a groove, the said off-center cylindrical opening and groove of the second link being adapted to cooperate and receive the cylindrical opening and projection of the first flanged portion and a clamping device for rigidly fastening the links in fixed relation when they are in aligned position extending through the corresponding openings.

4. A joint for fastening a plurality of metal links together, comprising a flanged portion on the end of one link having a laterally extending groove therein, a flanged portion on a second link having a laterally extending projection thereon adapted to cooperate with the groove on the first mentioned link, and means extending through openings in said flanged portions for securely holding said links in fixed relation to each other.

5. A joint for rigidly fastening a plurality of metal links together, comprising a flanged portion on the end of a link having a laterally extending lug provided with a groove at substantially right angles to the longitudinal axis of said link, a flanged por-

tion on the end of another link having a laterally extending lug provided with a projection thereon at substantially right angles to the axis of said link adapted to be received in the groove in the lug on said first
5 mentioned flanged portion, and means extending through openings in said lugs for rigidly securing said links together.

In testimony whereof, we have hereunto set
10 our names this 28th day of July, 1927.

WALTER E. LARSON.
JOHN H. KOHLER.
